UNITED STATES PATENT OFFICE.

RUDOLPH P. GILL, OF ORANGE, VIRGINIA.

SODA-FOUNTAIN.

1,321,731.

Specification of Letters Patent. Patented Nov. 11, 1919.

Application filed July 19, 1918. Serial No. 245,719.

To all whom it may concern:

Be it known that I, RUDOLPH P. GILL, a citizen of the United States, residing at Orange, in the county of Orange and State 5 of Virginia, have invented new and useful Improvements in Soda-Fountains, of which the following is a specification.

This invention relates to soda fountains, the broad object in view being to produce 10 a fountain, the main parts of which are combined in a novel way so that the whole fountain may be readily assembled and the parts thereof secured together without the use of bolts, screws and similar fastening devices. By reason of the construction hereinafter described, and claimed, the fountain structure, as a whole, is rendered especially sanitary, in that, certain parts thereof may be readily disassembled, enabling 15 the vital parts of the fountain structure to be thoroughly cleansed from time to time.

Another object of the invention is to provide a novel mounting for the syrup jars and the covers for the compartments to 20 which access must be frequently had; also to provide a novel interior arrangement of the main receptacle whereby it is divided into compartments but adapted to admit of the transmission of the chilled cold air and 25 the low temperature from one compartment to another.

With the above and other objects in view, the invention consists in the construction, combination and arrangement of parts, as 30 herein described, illustrated and claimed.

In the accompanying drawings:

Figure 1 is a perspective view of the improved fountain structure.

Fig. 2 is a vertical transverse section 35 through the same.

Fig. 3 is an end elevation of the fountain structure.

Fig. 4 is a fragmentary vertical longitudinal section through the same on the 40 line 4-4 of Fig. 2.

The improved fountain structure comprises a bottom wall, side walls 2 and 3 which may be termed the front and rear walls, and end walls 4. The bottom wall 1 is supported by bottom rails 5 which elevate the bottom wall 1 a suitable distance 45 above the floor line indicated at 6. The bottom wall 1 is formed adjacent to the margin thereof and in its under side with grooves 7 which receive tongues 8 on the upper sides of the supports 5 whereby an in-

terlocked connection is formed between said bottom wall and supporting rails 5 therefor. Said bottom wall 1 is formed along its margin with upstanding longitudinal 50 tongues 9 which are received in corresponding grooves 10 in the expanded bottom edges of the side and end walls 2, 3 and 4.

One of the side walls 2 which will constitute the front wall of the fountain structure is formed with an upright extension 11 which forms a vertical continuation of the main body of said wall and renders the said wall of suitable height to support a top slab or counter 12 having in the bottom 55 thereof a groove 13 which receives a tongue 14 extending longitudinally of the widened upper edge of the extension 11, as shown, the slab 12 thus having an interlocked connection with the extension 11. Brackets or 60 braces 15 are also provided between the extensions 11 and the top slab 12 to properly support the latter in a horizontal position as shown. Each of the brackets or braces 15 is formed with a tongue 16 and said 65 tongue is received in a groove 17 in the lower side of the slab 12.

Arranged within the walled structure hereinabove described is a cooling receptacle comprising a bottom wall 18, side walls 19 70 and end walls 20, the walls of said receptacle being arranged in spaced relation to the corresponding outer walls of the cabinet structure, and suitable insulating material 21 being packed between such inner and 75 outer walls to prevent the inside temperature of the cabinet from being affected by the outside temperature. The insulation space is closed at the top by a top wall 22 which has a tongue and groove joint connection at 23 with the outer and inner walls above described, the top wall 22 being thus held properly in its position. The interior of the inner receptacle is divided into compartments 24 and 25 by means of a 80 substantially upright heat conducting wall 26 preferably formed of sheet metal and vertically corrugated as shown at 27, to stiffen and strengthen the same. The bottom edge of the heat conducting wall or 85 partition 26 is bent and extended horizontally as shown at 28, and arranged in a groove or seat 29 of corresponding formation in the upper side of the bottom wall 18 wherein it is fastened by cement 30 90 which provides a liquid tight joint. The upper edge of the partition or wall 26 over-

laps and rests against a depending flange 31 on the bottom of the top wall 22 and said partition 26 is formed with openings 32 near its top edge to receive hook shaped lugs 33 projecting from the flange 31.

The top wall 22 is formed over the compartment 24 with a longitudinal series of openings 34 for the purpose of receiving a corresponding number of inclined syrup jaws 35. Each of said jars 35 has at one side thereof a supporting lip 36 which rests upon the adjacent part of the top wall 22. At its opposite side, each jar is provided with another supporting lip 37 which rests upon a complementary supporting lip 38 on the inside of an inclined jar supporting wall 39, the latter having an expanded bottom edge 40 which rests upon the top wall 22. The inclined wall 39 slants away from the front wall 2 and the extension 11 thereof and terminates flush with the top edges of the syrup jars 35. Each syrup jar 35 is provided along its top edge with an upstanding rib 41 while each individual jar cover 42 is formed in its under side with a groove 43 to fit the tongue 41. Each jar cover is thus properly held in place with respect to its jar. At the same time, the jar cover may be easily removed and in fact, the jar itself may be easily and entirely removed from the cabinet. Each jar cover 42 has secured thereto an upstanding syrup spout 44 and a syrup pump 45, said spout and pump extending upwardly from an attaching base 46 which is secured by suitable fastening means to the respective jar cover 42.

In the compartment 25, there is arranged an elevated porcelain well 47, designed to receive an ice-cream can. The well 47 is supported with its bottom elevated above the floor or bottom wall 18 of the cooling receptacle by legs 48 so that the cooling material may be placed all around and beneath said well 47. Above the well, the top wall 22 is formed with an opening 49 surrounded by an upstanding tongue 50 received in a corresponding groove 51 in the bottom of a cover 52, by means of which access may be had to the contents of the well 47. As many wells 47 and covers 52 may be employed as consistent with the size of the structure. The jar covers 42 have their adjacent edges jointed and overlapped as shown at 53 so that said jar covers may be removed without disturbing others.

Arranged in the compartment 25 are water coils 54 and 55 for cooling plain, uncharged or sweet water, and charged or carbonated water used to mix with the syrups. The uncharged water is admitted through an inlet 56 at one end of the cabinet, and the charged water is admitted through an inlet 57 at the same end of the cabinet. 58

designates an overflow pipe for one of the compartments 24 and 25, and 59 designates a drain cock to be used when cleaning out the fountain. 60 designates an overflow pipe for the other one of said compartments and 61 designates a drain cock for the same.

From the foregoing description, taken in connection, with the accompanying drawings, it will now be seen that the specified sectional construction of the cabinet or fountain structure, and the manner in which the several parts thereof are combined, provides for the rapid and easy disassembling of parts thereof which are necessary to enable the fountain structure, as a whole, to be thoroughly cleansed and maintained in a sanitary condition. When the parts are properly associated with each other, they have an interlocked or keyed connection with each other, so that there is no danger of such parts becoming displaced. Any desired material, such as marble, porcelain, slate, or the like, may be used in the formation of the main walls of the structure and, it will, of course, be understood that the sizes and proportions of the parts may be varied to suit the will of the manufacturer in accordance with the size and extensy of the complete outfit.

I claim:—

1. In a soda fountain, a cabinet embodying in combination, a bottom wall, side and end walls having a tongue and groove jointed and separable connection with each other and with said bottom wall, an inner refrigerating receptacle comprising integral side, end and bottom walls arranged in spaced relation to the corresponding first named walls, and a top wall separably supported upon both sets of said walls and having a tongue and groove jointed connection therewith.

2. In a soda fountain, a cabinet embodying in combination, a base, a bottom wall having tongue and groove connection with the top of said base, a front wall having tongue and groove connection with the forward edge of said bottom wall and having a portion engaging the front of said base, side and end walls having a tongue and groove connection with each other and with said bottom wall, an inner refrigerating receptacle including walls arranged in spaced relation to the casing formed by all of said walls, and a top wall detachably supported upon said side and end walls and said receptacle walls and having tongue and groove connection therewith, the forward edge of said top wall lying against the rear surface of said front wall.

In testimony whereof I affix my signature.

RUDOLPH P. GILL.
